DESIGN FOR A FILE FASTENER

Martin Pollock, Eastchester, N. Y.

Application September 30, 1942, Serial No. 108,370

Term of patent 14 years

To all whom it may concern:

Be it known that I, Martin Pollock, a citizen of the United States and a resident of the city of the town of Eastchester, in the county of Westchester and State of New York, have invented a new, original, and ornamental Design for a File Fastener, of which the following is a specification, reference being had to the accompanying drawing forming a part thereof.

Fig. 1 is a plan view of a file fastener, in separated position, showing my new design;

Fig. 2 is a plan view of one side thereof in assembled position; and

Fig. 3 is a plan view of the opposite side thereof in assembled position.

I claim:

The ornamental design for a file fastener, substantially as shown.

MARTIN POLLOCK.
